UNITED STATES PATENT OFFICE.

ALBERT E. BRIGHT, OF HOPEDALE, ILLINOIS.

SLIDING GATE.

SPECIFICATION forming part of Letters Patent No. 460,711, dated October 6, 1891.

Application filed June 12, 1891. Serial No. 396,974. (No model.)

To all whom it may concern:

Be it known that I, ALBERT E. BRIGHT, a citizen of the United States, residing at Hopedale, in the county of Tazewell and State of Illinois, have invented certain new and useful Improvements in Sliding Gates; and I do hereby declare the following to be a full, clear, and exact description of the invention, such as will enable others skilled in the art to which it appertains to make and use the same.

The special object of the invention is to provide convenient mechanism whereby a sliding gate may be moved back and forth, the latch being lifted by the same mechanism previously to opening the gate.

Figure 1 of the drawings is an end elevation; Fig. 2, a side elevation, and Fig. 3 a transverse vertical section on dotted line $x x$ of Fig. 2.

In the drawings, A represents the gate, which slides on flanged rollers KK, arranged between the two upper rails $a a'$, these rollers being pivoted on the posts L L'.

H is a latch having the notch h, which engages the cross-bolt s between two posts S S, which may also be connected at the top and near the bottom by the cross-bars s' s'. The lever-latch H is fulcrumed at h' on the vertical slat a^2 , so as to admit of being raised before the gate is opened.

E is a bar sliding on the stud J of the vertical slat a^3 , and slotted at e to allow of a movement on said stud before the gate begins to move back. This bar has a rod or extension F, whose front end is provided with a hanger G, which passes under the latch H. The rear end of said bar is arranged under a stud l on the post L and jointed to the lower end of the diagonal lever C. The latter is fulcrumed at c on the post L ^{2} .

I is a keeper arranged vertically, and a^3 a cross-brace to the gate, the two co-operating to guide and hold in its proper position the bar E and latch H.

The posts L L ^{2} are connected by the cross-bars R R ^{2} , and these by a vertical bar R ^{3} , while the post L ^{2} and vertical bar R ^{3} are connected by the horizontal bar R'.

D is a rod connected at one end by a pivot to the lever C, and pivoted at the other end to the lever E', the latter being fulcrumed to the vertical bar R ^{3} . The free end of lever E' has two rods N N rising vertically therefrom and connecting at the top with the levers T T, fulcrumed on the cross-beam W, which is supported by the braces V. The levers T T may have pendent rods t t within easy reach, one lever being on each side of the gate.

U represents a bottom guide for the gate as it slides back and forth.

The operation is as follows: The rod t is pulled downward and operates the mechanism so as first to lift the latch H and then to open the gate. When it is desired to shut the gate and latch it, the levers are operated in a reverse direction by pushing a rod t upward.

What I claim as new, and desire to protect by Letters Patent, is—

1. In mechanism for latching, unlatching, opening, and closing a sliding gate, the lever-latch H, the hanger G, and the slotted bar E F, combined with any suitable mechanism to move the bar E F back and forth, as described.

2. The combination, with the latch H, hanger G, and slotted bar E F, arranged, as shown, on a sliding gate, of the diagonal lever C, rod D, lever E', upright rods N N, the levers T T, and the rods t t, all arranged in connection with a superposed framing and posts, for the purpose set forth.

In testimony whereof I have affixed my signature in presence of two witnesses.

ALBERT E. BRIGHT.
